UNITED STATES PATENT OFFICE.

GUSTAV CLEMENS, OF BARMEN, GERMANY.

MITERING-MACHINE.

SPECIFICATION forming part of Letters Patent No. 629,425, dated July 25, 1899.

Application filed May 28, 1898. Serial No. 682,056. (No model.)

To all whom it may concern:

Be it known that I, GUSTAV CLEMENS, a subject of the Emperor of Germany, residing at Barmen, in the Province of Rhenish Prussia, Germany, have invented a new and valuable improvement in Mitering-Machines; and I do hereby declare that the following is a full, clear, and exact description of the construction and operation of the same, reference being had to the annexed drawings, making a part of this specification, and to the letters of reference marked thereon.

Figure 1 of the drawings is a vertical section of the complete machine. Fig. 2 is a plan. Fig. 3 is a side view. Fig. 4 is a front view. Fig. 5 is a plan showing a modified arrangement of the machine.

The nature of my invention consists in a supporting clamp or abutment secured to the bed-plate of the machine in such a manner that it may be adjusted, together with the working piece, in horizontal and vertical direction and in such levels which may be combined of both directions.

The invention further consists in the saw-guiding device, which is adjustable radially and in vertical direction, so that my improved mitering-machine is adjustable to admit any sized and shaped stick, molding, or board and any required miter, tenon, or tooth to be operated on.

The invention consists in the combination of certain parts and details and combinations of the same, as will be fully described hereinafter and then pointed out in the claims at the end of this specification.

In the accompanying drawings, *a* represents a rectangular or otherwise shaped base mounted on feet *b* and attached to a suitable bench or table. To the front of this base is fixed a bearing *c*, serving as a fulcrum for a fork *d*, which is turnably secured to the bearing by the nuts *c'*. The fork *d* is fitted with a horizontal bolt *e*, around which turns a clamp *f*, that serves as an abutment for the material being operated upon. In the present example the abutment consists of an angle-iron. It may be adjusted either in the horizontal plan, as shown in Fig. 2 by dotted lines, or in the vertical level, as illustrated in Fig. 1, or in

an angle which may be combined of both levels, as shown in Fig. 3, so that all admitted miters may be adjusted. To secure the abutment *f* in any of the positions, I have arranged a slotted bar *g*, which rests upon the base *a* and is guided thereon by means of a slot *h*, cut into the base, so that it can follow the horizontal adjustment of the clamp *f*, the vertical adjustment being obtained by the slot *g'*. Screws *i i'* serve to fix the adjusted position of the clamp *f*, which may be fitted with a gage for the purpose of cutting the moldings to the proper length.

The saw is guided by slotted posts *k*, which may be radially turned, raised, and lowered to operate a more or less high work without respect to the self-movement of the saw-blade. For this purpose I have fixed to the base two upright standards *l*, on which may be moved up and down sockets *m* and fixed to the standards in any position by set-screws *m'*. A round bar *n*, running across the base *a*, is fixed to the sockets *m*, carrying the posts *k*, which on said bar may be turned radially and raised or lowered, as shown in Fig. 3, in order to cut any tenon, tooth, and the like in any miter on the work. As shown in Fig. 5, I can also turn the whole saw-guiding device against the base *a* by separating both parts and arranging a vertical bolt *o*, allowing the turning of the guiding device.

The guide-post *k* is shown in Fig. 1 by a vertical section. It consists of the slotted tubular post *k*, in which is guided a hollow casing *r*. Two vertical rollers *u* are arranged rotatably therein, having collars *s* to receive and guide the saw-blade *t*, which by means of side strips *t'*, passing between the rollers, engage the collars and force the casing *r* to move up and down within the tubular post *k*.

To limit the downstroke of the saw-blade, I fix to the post *k* an adjustable set-angle *v*, upon which the casing comes to rest in the adjusted lowest position.

Having now fully described my invention, I declare that what I claim is—

1. In a mitering-machine the combination with a base, a gage adjustable horizontally and vertically or in any combination of these directions and means for securing the gage at

the desired adjustment, of a saw-guiding device arranged in front of the base adjustable on a horizontal axis and means for vertically adjusting such axis substantially as specified.

2. In a mitering-machine the combination of a crosswise-pivoted clamp, means for locking the clamp at the desired angle, a saw-guide consisting of slotted tubular posts which are radially turnable secured to a bar said bar being adjusted to sockets said sockets being

movable in vertical direction on standards substantially as specified.

In testimony that I claim the foregoing as my invention I have hereto affixed my signature in the presence of two subscribing witnesses.

GUSTAV CLEMENS.
